UNITED STATES PATENT OFFICE.

THOMAS WIGHT, OF KANSAS CITY, MISSOURI, ASSIGNOR TO FRANK TILK ORNAMENTAL IRON WORKS CO., OF KANSAS CITY, MISSOURI, A CORPORATION OF MISSOURI.

DESIGN FOR A LAMP-BRACKET.

43,975.

Specification for Design.

Patented May 6, 1913.

Application filed November 20, 1912. Serial No. 732,592. Term of patent 7 years.

To all whom it may concern:

Be it known that I, THOMAS WIGHT, a citizen of the United States, residing at Kansas City, in the county of Jackson and State of Missouri, have invented a new, original, and ornamental Design for a Lamp-Bracket, of which the following is the specification, reference being had to the accompanying drawing, forming part thereof.

The figure is an elevation of a lamp bracket, showing my new design.

I claim:

The ornamental design for a lamp bracket as shown.

THOMAS WIGHT.
